UNITED STATES PATENT OFFICE.

LOUIS M. HOOPER, OF RUTHERFORD, NEW JERSEY, ASSIGNOR TO THE
J. L. MOTT IRON WORKS, OF NEW YORK, N. Y.

WASTE-VALVE FOR BASINS OR BATHS.

SPECIFICATION forming part of Letters Patent No. 634,347, dated October 3, 1899.

Application filed October 24, 1895. Serial No. 566,714. (No model.)

To all whom it may concern:

Be it known that I, LOUIS M. HOOPER, a citizen of the United States, residing at Rutherford, in the county of Bergen and State of New Jersey, have invented an Improvement in Waste-Valves for Basins or Baths, of which the following is a specification.

This improvement relates to that class of basin and bath fittings in which there is a valve at the bottom of the basin and above the upper end of the waste-pipe, such valve being lifted to allow the water to run off.

In my present improvement the waste-pipe is made with a curve or bend, so as to make use of a valve-lifter in the form of a rod passing vertically, or nearly so, through the bend of the waste-pipe and acting upon the valve, and I provide mechanism for acting upon the lifter, and the valve and its stem are constructed in such a manner that the valve can be easily lifted out for cleansing, and the valve-stem is tubular and extends down around a tubular support for the valve-lifter, the parts being constructed in such a manner that there is little or no risk of water leaking out around the valve-lifter, and I provide a packing at this place to render the parts reliably tight.

In the drawings, Figure 1 is a vertical section of a basin with my improvements applied. Fig. 2 is a vertical section showing a portion of a basin with a modified valve-lifter. Fig. 3 is a vertical section at right angles to Fig. 2, showing the toggle-links above the handle-lever; and Fig. 4 is an inverted plan of the valve separately. Fig. 5 is a section of a modification in the escape or waste pipe.

The basin A is of any desired size and character, and it may be provided with the overflow-pipe B and a removable screen of ordinary character, as shown at C, Fig. 2; but in Fig. 1 I have shown the peculiar screen or grating C, hereinafter described. At the bottom of the basin there is an opening to which the waste-pipe D is applied. This waste-pipe is made as an offset elbow or compound curve in order that the lifter E for the valve F may be central with the opening in the basin and pass through the pipe to the actuating device. I provide a tubular guide 2, extending up into

the waste-pipe, and the valve F is at the upper end of a stem 3, and such valve fits the seat at or near the level of the bottom of the basin A, and the valve-stem 3, being tubular, sets around the tubular guide 2, so that water as it descends into the waste-pipe will be deflected by the tubular stem 3 of the valve and kept outside of the tubular guide 2 for the lifter. Hence there will be but little risk of leakage around the tubular guide 2; but in order to make a more reliable joint at this place the packing-gland 4 is employed, the same having a cap that screws upon the ferrule or nipple that projects downwardly from the waste-pipe D.

In order to actuate the lifter E, any suitable mechanism may be employed, according to the character of basin or bath fixture. In Fig. 1 I have represented a curved rod K as connected to the lower end of the lifter E, the shape of such rod being approximately that of the side of the basin, so that it can pass from the lower end of the lifter E through the slab M, at which place the handle H is provided, and it is advantageous to make the stem of the handle H tubular to pass through the thimble N, that is provided at the opening through the slab M, and the tubular stem 1 of the handle H is screw-threaded on its inner surface to receive the tubular screw-threaded sleeve 7, which can be raised or lowered within the tubular stem 1 of the handle, and there is a shoulder or offset upon the rod K that rests upon the upper end of the sleeve 7, and it is to be understood that this sleeve 7 is adjusted so that the valve F will take its seat properly upon the valve-seat F' when the handle H rests upon the thimble N, and it is advantageous to provide a pin 8, connected with the tubular stem of the handle H, which pin passes into a slot in the thimble N, which slot is L-shaped or inclined, so that the pin supports the handle and the valve when raised by a partial rotation given to the handle to turn the pin into the horizontal portion of the L-shaped or inclined slot. The lower end of the rod K is preferably within a horizontal sleeve 16, extending out from the lifter E, so as to allow for slight differences in the fitting of the parts in place on the slab.

The grating or strainer C is applied at the upper end of the overflow-waterway B, and in consequence of the upper end of this waterway being at an inclination, as represented in Fig. 1, the grating C will rest thereon by gravity, and it may be lifted off for cleaning the grating or for cleaning the overflow-waterway.

The modified devices shown in Figs. 2 and 3 act to raise or lower the valve F² in the same way as the devices represented in Fig. 1; but in some instances the distance of the lifter E from the edge of the basin is such that a bent rod, such as shown at K, does not work freely. To avoid this difficulty, the lifting devices may be arranged as next described.

The handle-lever H' has a T-shaped lower end, to which the links I K' are pivoted and extend to the lever L, that is pivoted at one end to the lifter E, and this handle-lever H' extends down through the slab M and slotted plate N' upon the slab and between the forked support O, that is attached at the under side 25 of the slab, and there is a pivot-pin 5 for the handle-lever H', such pivot-pin passing through a slot or elongated hole in the forked support O, and one of the links I or K' is provided with a turnbuckle P between the two 30 parts of the link, which two parts are threaded with right and left handed screw-threads, so as to adjust the relative lengths of the two links to bring the end of the lever L and the valve-lifter E in the proper position for 35 the valve to rest upon its seat when the handle-lever L is moved in one direction, and when such handle-lever is moved in the other direction the valve is raised vertically, so as to open the waste.

If it is desired for the waste to close automatically, the devices before described alone are required; but if it is desired to hold the waste open then the links S may be made use of, they being connected at their upper ends 45 upon the sides of the handle-lever, and their lower ends are pivoted at 6 in the forked support O, so that when the handle is moved in one direction these links S are swung so that the weight of the parts is sufficient to prevent 50 the valve acting through the lever L and links I K', swinging the handle-lever H' back again to its normal position for allowing the valve E to drop to its seat; but when power is applied by the hand to the upper end of the lever H' the toggle-links S are swung over 55 so as to lift the handle-lever as it is brought back to a normal position to allow the valve to close. By this construction it will be apparent that the two links I K' allow for the 60 proper motion to be given to the lever L, lifter E, and valve F² without the lever L having a rigid pivotal support from the lower side of the slab or other point of connection, and the parts can be finished and made ornamental 65 in cases where the basin is not inclosed below the slab. The valve may have a rubber edge and be connected loosely to the stem by a

screw 8, as shown in Fig. 2, to allow the valve to seat itself at the upper end of the waste-pipe, and there may be guide-pins 9 to center 70 the spindle within the waste-pipe.

In Fig. 1 the basin A is shown with an overflow B, having an inclined upper end below the top edge of the basin, and there is a perforated plate or grating C, that rests in a seat 75 at the upper end of such overflow, and to hold the grating in place the spring 12 is used, having downwardly-curved ends to snap down below a rim or offset around within the seat. In Fig. 5 the porcelain of the basin at the 80 lower part of the overflow extends below the seat F³ in the porcelain, which seat receives the valve F⁴, and the lifter E² in this case passes through the porcelain, and there is a packing-gland 14 in the porcelain that forms 85 a water-tight packing for the valve-stem. The rod K², that is to extend down from the handle or pull H, Fig. 1, passes through a tubular foot 16 at the lower end of the valve-stem. This allows for inequalities in the shape 90 of the porcelain basin and of the connection to the handle H, because the position of the tubular foot of the valve-stem along upon the rod K² may vary. The thimble 17, that is connected to the metallic waste-pipe, can be secured to the porcelain by flanges and a lock-nut, as usual. The valve F or F⁴ may be lifted off the stem for cleaning the valve and for giving access to the overflow-waterway 95 for cleaning the same, and a chain 18 is usually provided to prevent loss of such valve. This chain is secured to an eye 29 with a screw passing through the porcelain near the upper end of the overflow, and the nut 20, that secures this screw, is in such overflow. The 100 hook 21 on the screw receives the valve-ring 19, so that such valve can be hung up within the basin, and the slab is not injured or soiled by the valve being laid down upon it.

I do not claim a valve with a stem passing through the waste-pipe nor a lever to act upon such stem, as these have been used; but where the lever intervenes between the handle and the valve and is partially supported by the waste-pipe the strain comes on the 115 pipe, tending to loosen the joints. By my improvement the lift is direct upon the valve and there is nothing to disturb the setting of the basin or bath, and by making the waterway in the form shown in Fig. 5 the lifter passes through a packing-gland at the opening 120 through the porcelain of the basin, which renders the attachment very simple, and in all cases the weight of the handle and its rod tends to keep the valve on its seat instead of 125 tending to raise the valve, as is the case where a lever intervenes.

I claim as my invention—

1. The combination with a basin, bath or other sanitary fixture having a waste-opening and a waterway below the same, of a valve with a hollow stem, a tubular guide passing up within the said hollow stem and a valve-lifter within the tubular guide passing through the

wall of the waste-pipe, substantially as set forth.

2. The combination with a basin, bath or other sanitary fixture having a waste-opening and a waterway below the same, of a valve with a hollow stem, a tubular guide passing up within the said hollow stem and a valve-lifter within the tubular guide, and a packing-gland at the lower wall of the waste-pipe, through which the lifter passes, substantially as specified.

3. The porcelain basin having a waste-opening and a horizontal waterway below the same all in one piece, in combination with a valve-seat and a valve and a packing-gland in the opening in the porcelain and a vertical lifter passing through the packing-gland, substantially as set forth.

4. The combination with the bath or other sanitary fixture having a waste opening and pipe, of a valve and hollow stem, a stationary tubular guide within the valve-stem and passing through the wall of the waste-pipe, a pack-

ing-gland, a valve-lifter passing through the packing-gland and tubular guide, a tubular foot at the lower end of the valve-stem and a rod passing into such tubular foot and extending up through the slab for lifting the valve, substantially as specified.

5. The combination with the porcelain basin having a waste-opening and horizontal waterway below the same all in one piece, of a valve-seat and valve and a packing-gland in an opening in the porcelain and a vertical valve-lifter passing through such packing-gland, a tubular foot at the lower end of the valve-lifter and a rod passing into such tubular foot and extending up and passing through the slab for raising the valve, substantially as set forth.

Signed by me this 21st day of October, 1895.

L. M. HOOPER.
